INTRODUCTION

UNITED STATES PATENT OFFICE.

WILLARD F. MEYERS, OF NEW YORK, N. Y.

STONEWORKING-MACHINE.

1,027,558.

Specification of Letters Patent. Patented May 28, 1912.

Application filed December 5, 1908. Serial No. 466,064.

To all whom it may concern:

Be it known that I, WILLARD F. MEYERS, a citizen of the United States, residing at Long Island City, borough of Queens, city of New York, in the county of Queens and State of New York, have invented a certain new and useful Improvement in Stoneworking-Machines, of which the following is a specification, reference being had therein to the accompanying drawings, forming part thereof.

My invention relates to machines for dressing stone, and has for its objects the production of a machine of simple and improved construction and having a wide range of utility, capable of performing its work rapidly and accurately, with improved capacity of adjustment and convenient operation, for the purpose of grinding, surfacing and polishing stone.

Other objects and advantages will appear from the following description.

My invention includes means for regulating the pressure on the grinders, and also means for automatically lifting the grinders from one stone to another of a different thickness; and my invention further includes means for limiting and regulating the depth of cut of the grinders.

My invention also includes a stationary table and means for feeding the grinders in two directions relatively to the table, such grinders rotating in planes substantially parallel with the face of the table.

My invention also includes other advantageous features and details of construction, as will hereinafter appear.

While my present invention is more particularly directed to the devices for effecting the grinding and polishing operations, as a matter of great convenience, I have embodied in one machine, in addition to the grinding devices, a reversible head carrying jointing saws set at different angles, for cutting the stone in different directions.

I shall now describe an embodiment of my invention with reference to the accompanying drawings and shall thereafter point out my invention in claims.

Figure 1 is a plan view, with parts broken away, of a machine embodying my invention. Fig. 2 is a side elevation, partly broken away. Fig. 3 is an end elevation, partly in section, as viewed from the right of Figs. 1 and 2. Fig. 4 is an enlarged de-

tail view showing a locking device for limiting and regulating the depth of cut of the grinders, as viewed from the right of Fig. 3. Fig. 5 is a vertical section on planes indicated by the line 5—5 of Fig. 1, looking upward. Fig. 6 is an elevation of the jointing saw head and carriage as viewed from the left of Figs. 1, 2 and 5, and as viewed from the rear of Fig. 3, portions of the frame also being shown. Fig. 7 is an elevation of the supporting carriage for the jointing saw head and its immediate adjuncts, the jointing saw head being removed. Fig. 8 is a sectional plan on a plane indicated by the line 8—8 of Fig. 2, portions being omitted. Fig. 9 is an elevation of a portion of the grinder head supporting carriage and its immediate adjuncts, including particularly portions of the feeding mechanism. Fig. 10 is an enlarged vertical section on a plane indicated by the line 10—10 of Fig. 2, as viewed from the left, portions being broken away. Fig. 11 is a horizontal section on a plane indicated by the line 11—11 of Fig. 10.

The illustrated embodiment of the invention comprises a plurality of grinders mounted to rotate in horizontal planes, feeding mechanism for feeding the grinders in two directions over a stationary work-supporting table, means actuated by the feeding mechanism for automatically lifting the grinders from one piece of work to another, combined counterbalancing and pressure augmenting weights for the grinders, and an adjustable locking device for determining the maximum depth of cut of the grinders. Also two jointing saws are provided and are set in planes substantially at right angles, and the jointing saws are mounted on a swivel head so as to bring either of the saws into operative position relatively to the work, for cutting the stone either longitudinally or transversely as desired, means being provided for feeding the saws according to the direction of the cut to be made.

The work is supported on a substantially horizontal bed or work-supporting table 13 above which the grinders 14 are hung. The grinders 14 are for grinding, surfacing and polishing, four of such grinders being shown in the drawings. These grinders 14 are mounted on vertical shafts 15 journaled in shaft hangers or shaft bearings 16, and the shafts 15 are free to move vertically in the hangers 16 for permitting the grinders 116

to rest upon and be pressed against the work. Means are provided for regulating the pressure on the grinders, that is, for varying the force with which the grinders are pressed toward the work. For increasing and for decreasing the pressure on the grinders, substantially horizontal levers 17 are provided and have fulcrum pivots supported by depending brackets or supports 18, extending from the shaft hangers 16. The levers 17 are pivoted to the grinder shafts 15, so as to partake of the vertical movement of the shafts, by means of relatively loose collars 19 which are prevented from sliding longitudinally on the shafts 15 by fixed collars 20 and have a slotted pivotal connection with the levers 17, as shown in Figs. 2 and 5. Arms of the levers 17 extend forward some distance from the shafts 15 and other arms of these levers extend rearwardly from the fulcrum pivots of the levers, and weights 21 are provided and are applicable to or may be adjusted to either the front arms or to the rear arms of the levers and are slideable along the levers toward and away from the fulcrum pivots, for varying the pressure of the grinders 14 on the work. The weights 21 are shown as held in adjusted position by set screws 12 (Figs. 1, 2, 3 and 5), indentations or recesses 12^a (Figs. 2 and 5) being shown as provided in the lever arms for receiving the ends of the set screws. In the drawings the weights 21 are shown as applied to the forward or outer ends of the levers 17, and when the weights 21 are in this position they augment the pressure of the grinders 14 on the work, that is to say, the downward pull of the weights 21 is added to that due to the weight of the grinders 14 themselves and of their shafts 15, to increase the pressure of the grinders on the work. The pressure of the grinders on the work may be increased to a greater or less extent by shifting the weights 21 along the forward lever arms. If the weights 21 be removed from the levers 17 then another phase of adjustment is secured in which the pressure of the grinders on the work is substantially equal to the weight of the grinders and their shafts. The weights 21 may be placed on the rearwardly extending arms of the levers 17 and in this position of adjustment the weights 21 will exert a lifting or counterbalancing effect on the grinders 14, and the counterbalancing effect may be regulated by adjusting the weights along the lever arms. By thus partially counterbalancing the grinders to a greater or less extent the pressure of the grinders on the work may be decreased or lessened to any desired amount and may be rendered ever so slight, so as to be suitable for fine polishing operations.

To regulate the depth of cut of the grinders cam toes 22 are splined on a rock shaft 23 and are adapted to engage the upper sides of the rearwardly extending arms of the levers 17 and to limit the downward movement of the grinders 14 toward the work. The cam toes 22 are provided with flanged sleeves 139 journaled in bearings 140 on the lever supports 18, so that the toes 22 are kept in operative relation to the levers 17, regardless of the feeding or adjustment of the shaft hangers 16 longitudinally to the rock shaft 23. The depth of cut of the grinders 14 may be varied by rotating the rock shaft 23 and locking the same in the desired position. The rock shaft 23 is supported in downwardly extending brackets 24, extending from a cross frame 39, and at one end, shown in the drawings (Fig. 3) as at the right side of the machine when viewed from the front, is provided with a hand lever 25 for rocking the shaft 23. To retain the rock shaft 23 in any position to which it may be rocked this shaft is provided with a limiting arm 26 which is adapted to engage with a stop pin 27 carried by a regulating disk 28 rotatably mounted on the shaft 23 and adapted to be held in adjusted position by a thumb nut 29 screwed on a stud 30 projecting from one of the supporting brackets 24 through a slot 31 in the disk 28 (see particularly Fig. 4). By the means described the depth of cut of the grinders 14 may be regulated so as to cut down to a predetermined level or plane and to go no deeper, and in this way a uniformly smooth plane surface may be produced.

The grinders 14, levers 17 and shaft hangers 16 are supported by a carriage 32. The shaft hangers 16 are attached to the carriage 32 by bolts 33 engaging in T-shaped slots extending the length of the carriage 32. This construction permits the adjustment of the hangers 16, together with the grinders 14, to different distances apart, by sliding the bolts to different locations along the slots, and also, by the same means, permits the employment of a greater or less number of grinders, as desired.

To actuate the grinders 14 bevel gears 34 are provided with sleeves 35 (shown in dotted lines in Fig. 5) journaled in the upper parts of the hangers 16 and having, as indicated, a splined connection with the actuating shafts 15 of the grinders 14, so as to permit actuation of the grinders without regard to their vertical movement relatively to the shaft hangers 16. The gears 34 are adapted to be rotated by bevel gears 36 provided with flanged sleeves 37 journaled in brackets shown as formed integral with and extending upwardly from the shaft hangers 16. All of the gears 36 are splined on a single driving shaft 38, so as to permit actuation of the grinders 14 without regard to the adjustment of the shaft hangers 16.

along the carriage 32 or to the feeding of the carriage 32, together with the grinders, longitudinally to the actuating shaft 38.

The carriage 32, together with the parts 5 carried thereby, is arranged to have a reciprocatory feed movement transversely to or crosswise of the table 13, and to permit this feed movement the carriage 32 is mounted to slide longitudinally on the horizontal cross frame 39. The carriage 32 is held in place and guided on the frame 39 by dovetail gibbs on the carriage which engage with dovetail ways on the frame, as shown in the drawings (see Fig. 5 particularly). 10 Means are provided for feeding the grinders 14, carried by the carriage 32, back and forth across the work at substantially an even rate of movement, so as to substantially equalize the grinding and polishing 15 operations at different points of the feed movement. To effect this feed movement a pitman or connecting rod 40 connects the carriage 32 with a crank 41 fixed on a short shaft 42, as appears most clearly in Fig. 9. 20 The shaft 42 also has fixed thereon an elliptical gear wheel 43 which meshes with and is driven by another elliptical gear wheel 44 in such manner as to carry the crank 41 quickly over the dead center and to compensate for the differences in rectilinear movement caused by the angular movement of the crank. The elliptical gear wheel 44 is fixed on a shaft 45 on which is also fixed a worm wheel 46 engaged by a worm 47 25 carried on a feed shaft 48. The feed shaft 48 is connected with the driving shaft 38, to be rotated thereby, by a sprocket chain 49 engaging sprockets 50 and 51. The driving shaft 38 is supported on the frame 39 in 30 bearings 52, and the feed mechanism just described is supported by a bracket 53 secured to the frame 39. The driving shaft 38 is shown as arranged to be actuated by an electric motor 54 mounted on the frame 39 and connected to the shaft 38 by bevel gears 55 and 56, the latter gear being fixed 35 on the driving shaft 38.

Means are provided for raising and lowering the grinders 14 through a considerable 40 range of movement so as to bring them to the proper height to act on stones of considerable difference in thickness supported on the table 13, and this vertical adjustment is effected by moving the frame 39 vertically. 45 To permit of this adjustment the grinder carrying frame 39 is mounted to slide vertically on a main supporting frame 57 and is guided thereon by flanges as shown in the drawings (see particularly Fig. 8), and to effect this vertical adjustment lifting 50 screws 58 are journaled on the main frame 57 and have screw-threaded engagement with opposite ends of the grinder-carrying frame 39. These lifting screws 58 are of the same pitch and are connected together

to be operated in unison at the same rate so that the frame 39 may be adjusted up and down with an equal and parallel movement of all its parts. To actuate the lifting screws 48 in this manner, these screws are 70 connected together and adapted to be actuated by a transverse shaft 59 journaled on the main frame 57 and geared to the lifting screws 58 by worm gears as shown in the drawings. The weight of the frame 39 and 75 of the mechanisms carried thereby is supported by the lifting screws 58. Desired vertical adjustment may be manually effected by means of a grooved pulley wheel 60 fixed on one end of the adjusting shaft 59 80 and engaged by a hand rope 61.

In addition to the reciprocatory feed movement of the grinders 14 transversely of the table 13, means are provided to feed the grinders longitudinally of the table 13, 85 and this longitudinal feed movement of the grinders is effected by feeding the main frame 57 longitudinally of the table 13. By feeding the main frame of the machine along a stationary table or work-supporting bed, 90 it is obvious that the machine can be operated in one-half the space that would be required if the work-supporting bed or table were fed past a stationary main frame, or else for the same space the stationary table 95 may be of twice the capacity of a table that has a feed movement. The main frame 57 is supported and guided in V guides or ways formed in side rails 62 shown as secured by bolts to the bed 13, and is held in 100 place on the rails by toes 63 engaging under overhanging portions of the table as shown. Provision is made for taking up wear by raising the rails 62 by means of screws 64 screwing into bosses 65 formed 105 on base flanges extending from the bed 13. The main frame 57 is fed along the rails 62 by longitudinally arranged feed screws 66 journaled in stationary bearing blocks 67. The feed screws 66 pass through and have 110 screw-threaded engagement with nuts 68 (see particularly Figs. 10 and 11) embraced and held by collars 69 held between portions of the main frame 57 forming abutments, as seen most clearly in Fig. 2. The nuts 68 115 have formed thereon worm gears 70, which also act as thrust bearings for the collars 68, additional thrust bearings being provided by annular ribs on the nuts engaging in grooves in the collars (Fig. 11). 120

It is evident that the main frame 57 may be fed along the rails 62 either by rotating the nuts 68 or by rotating the screws 66. To impart the necessary feed movement in the operation of the machine, means are provided for rotating the nuts 68 at the proper rate while the screws 66 remain stationary, and to move the grinders quickly from one piece of work to another or from one part of the work to another part, means are pro- 125 130

vided for rapidly rotating the feed screws 66 without rotation of the nuts 68.

The means for rotating the nuts 68, to feed the grinders 14 longitudinally of the table 13, will be first described. The worm gears 70 are engaged by worms 71 formed at the lower ends of vertical sleeves 72 journaled in the main frame 57. Vertical shafts 73 and 74, journaled at their lower ends in the worms 71 and sleeves 72 and journaled at their upper ends in the main frame 57, are adapted to be connected respectively with the sleeves 72 by ordinary tooth clutches 75 to rotate the worms 71. The upright shafts 73 and 74 are geared to a cross shaft 76 journaled in bearings on top of the main frame 57. Two bevel gears 77 and 78 are loosely mounted on the cross shaft 76 between two of its bearings and are rotated in opposite directions by a bevel pinion 79 carried on the motor shaft of an electric motor 80 mounted at the top of the main frame 57. A tooth clutch 81 (Fig. 1) of ordinary form is arranged between the two gears 77 and 78 so as to engage them alternately with the cross shaft 76, to drive this shaft in either direction, for feeding the main frame 57, carrying the grinders 14, in either direction longitudinally of the table 13, as desired.

The means for rapidly rotating the feed screws 66, to quickly move the main frame 57 and mechanisms carried thereby, comprise a connecting shaft 82 geared to the ends of the screws 66 and passing loosely through two bevel gears 83 and 84 both engaged by a bevel pinion 85 directly rotated by an electric motor 86. A tooth clutch 87 of ordinary form is arranged between the gears 83 and 84 so as to engage either one or the other of these gears with the connecting shaft 82, so that the shaft 82 may be rotated in either direction, to move the main frame 57 toward either end of the table 13.

Different parts of the work or different pieces of work supported on the table 13 sometimes have their upper sides or upper surfaces at different levels, and means are provided for lifting the grinders 14 from one location on the work and for letting them down again at another location on the work, and such means are arranged to be actuated automatically as the main frame 57 is moved over the table 13. A vertically arranged push rod 87 is guided in the main frame 57 and is provided at its upper end with a lifting toe 88, which engages beneath an arm 89 fixed on the adjacent end of the rock shaft 23 and extending on the opposite side of the rock shaft from the cam toe 22. The lower end of the push rod 87 carries a roller 90, which, as the main frame 57 moves along the rails 62, is arranged to travel along a track 91 supported on one of the side rails 62.

A lifting cam or cam block 92 is arranged in

the path of the roller 90 and is adjustable along the track 91 by means of set screws, as shown in the drawings (Figs. 2 and 3). The lifting cam 92 is provided with oppositely inclined faces, as shown, and when 70 the roller 90 rides over the lifting cam the push rod 87 will be actuated to rotate the rock shaft 23 so as to depress the cam toes 22 against the rearwardly extending arms of the levers 17 and thereby raise the grinders 14; 75 and as the roller 90 travels down the opposite incline of the lifting cam, the grinders 14 will be gradually let down again at a new location on the work which may be at a higher or at a lower level. It is obvious that as many lifting cams 92 as desired may be employed at different locations along the track 91.

Means have been described for grinding and polishing the surfaces of stones, and 85 the means embodied in the same machine for cutting the stones both in a lengthwise and in a crosswise direction will now be described. A jointing saw 93 is provided for cutting the stone lengthwise or longitudinally of the table 13, and another jointing saw 94 is provided for cutting the stone crosswise or transversely of the table 13, and means are provided for bringing either of these saws into operative relation with 95 the work supported on the table. The jointing saw 93 is arranged parallel with the length of the table 13 and is mounted on a stub shaft 95 journaled in a shaft hanger 96 vertically adjustable in dovetail 100 guides or ways 97 on a reversible swivel head 98. Adjustment of the shaft hanger 96 relatively to the swivel head 98 is effected by means of a screw 99 (Fig. 6) journaled in bearings on the swivel head as shown and 105 having screw-threaded engagement with a lug 100 carried by the shaft hanger 96, and arranged to be actuated by bevel gears 101 and a hand wheel 102.

The jointing saw 94 is arranged cross- 110 wise of the table 13 and in planes substantially at right angles to the other jointing saw 93. The jointing saw 94 is mounted on a stub shaft 103 journaled in the opposite end of the shaft hanger 96 and which, in 115 the positions of the parts as illustrated in the drawings, is the upper end of the shaft hanger. The shaft hanger 96 is reversible end for end to bring either the one or the other of the jointing saws into lowermost 120 position and into operative relation to the work supported on the table 13, and to thus reverse the position of the shaft hanger 96 the swivel head 98, on which the shaft hanger 96 is mounted, is reversed in position. To permit of this reversal, the swivel head 98 has on its rear face an annular rib which is guided in an annular groove in a supporting carriage 104, and the swivel head 98 is shown as held in position 130

5 by bolts 105 (Fig. 6), engaging in an annular T-slot in the carriage 104 outside of and concentric with the annular guide groove. It is evident that the adjusting screw 99 serves as well for the jointing saw 94 as for the jointing saw 93.

10 To actuate the jointing saws 93 and 94, the jointing saw shafts 95 and 103 are geared, by bevel gears 106 and 107, to alined shafts 108 and 109 journaled in the shaft 15 hanger 96 and passing loosely through flanged sleeves 110 and 111 journaled in the swivel head 98, the vertical shafts 108 and 109 being provided with fixed thrust collars 112 and 113. The sleeves 110 and 111 20 carry bevel gears 114 and 115, respectively, and both of these bevel gears are engaged by a bevel gear 116 having a sleeve portion journaled concentrically in the swivel head 98, so that the bevel gear 116 is adapted to 25 drive either of the jointing saws 93 or 94. To actuate the saws 93 and 94, the alined shafts 108 and 109 may be engaged with the sleeves 110 and 111, respectively, to be 30 rotated thereby, by ordinary tooth clutches 117 and 118 splined on the shafts 108 and 109, respectively, to permit actuation of the jointing saws without regard to their 35 adjustment relatively to the swivel head 98. Because of the fact that the sleeves 110 and 111 are loose on the shafts 108 and 109, respectively, when the shaft hanger 96 is 40 adjusted across the swivel head 98 to a sufficient extent, the shaft 108 may enter the sleeve 111 and, in the opposite phase of adjustment, the shaft 109 may enter the sleeve 110 without interfering with the actuation of the jointing saws, thus permitting 45 of a considerable range of adjustment by manipulation of the screw 99. A bevel gear 119 faces in the opposite direction to gear 116 and is connected therewith by a connecting shaft 120 (Figs. 6 and 7). The bevel gear 119 is actuated by a bevel gear 121 50 shown as formed with a flanged sleeve journaled in the carriage 104 (Fig. 8), and the gear 121 is shown as having a splined connection with a horizontal jointing saw driving shaft 122, so as to permit actuation 55 of the jointing saws without regard to movement of the carriage 104 longitudinally to the driving shaft 122.

60 The carriage 104, together with the jointing saws carried thereby, is arranged to have horizontal feed movements both crosswise and longitudinally of the work-supporting bed or table 13. To permit of the crosswise feed, the carriage 104 is mounted to slide longitudinally on a horizontal cross frame 123. The carriage 104 is held in place and guided on the frame 123 by dovetail gibbs on the carriage which engage with dovetail ways on the frame, as shown in the drawings (see Fig. 5). To feed the 65 carriage 104 along the ways longitudinally

of the frame 123, a feed screw 124 is journaled at its ends in the frame 123, extending from end to end of such frame, and has screw-threaded engagement with the carriage 104 (Fig. 5). A screw-actuating spur gear 125 is loosely mounted on one end of the feed screw 124 and is adapted to be engaged with or connected with such feed screw and disconnected therefrom by an ordinary tooth clutch 126. The gear 125 70 is engaged by a pinion 127 carried by the adjacent end of the jointing saw actuating shaft 122, this shaft extending the length of the frame 123 in parallel relation to the feed screw 124 and being journaled at its 75 ends in the frame 123. The end of the feed screw 124, outward from the clutch 126, is squared, as shown, for the attachment of a crank to adjust the carriage 104 along the 80 frame 123 independently of the feed movement of the carriage. 85

To accommodate work at different heights or of different thicknesses, the jointing saw supporting cross frame 123 may be raised and lowered or vertically adjusted through 90 a considerable distance, and to permit of this adjustment the frame 123 is mounted to slide vertically on the main supporting frame 57 and is guided thereon by flanges (Fig. 8) similarly to the grinder supporting frame 39. This vertical adjustment is effected by lifting screws 128 journaled on the main frame 57 and having screw-threaded engagement with opposite ends of the frame 123. The screws 128 are of the same pitch 95 and are connected together to be actuated in unison by a connecting shaft 129 journaled on the main frame 57 and geared to the lifting screws 128 by bevel gears as shown in the drawings, so that the frame 123 may be 100 adjusted vertically with an equal and parallel movement of all its parts. The weight of the frame 123 and of the mechanisms carried thereby is supported by the lifting screws 128. Vertical movement of the frame 105 123 is effected by a grooved pulley 130 fixed on one end of the connecting shaft and engaged by a pull rope 131.

The jointing-saw driving shaft 122 is arranged to be actuated from the vertical shaft 115 74, which, as above described, together with the vertical shaft 73, feeds the main frame 57 longitudinally of the table or bed 13. The frame 123 carries a supporting bracket 120 132, in which is journaled a flanged sleeve 133 of a bevel gear 134, which is splined on the vertical shaft 74, so as to permit actuation of the jointing saws without regard to the vertical adjustment of the jointing saw supporting frame 123 on the main frame 57. 125 The gear 134 engages a bevel gear 135 (Fig. 8) also journaled on the bracket 132, and carrying a sprocket wheel 136 connected by a sprocket chain 137 with a sprocket 138 fixed on the jointing-saw driving shaft 122. 130

The jointing saws are fed longitudinally of the table 13 by feeding the main frame 57 by the same means employed in giving a like feed movement to the grinders 14, and described above. It is evident that the same advantages accrue in feeding the jointing saws past a stationary work-supporting table that are described in reference to the feed of the grinders 14. When the jointing saws are to be used, the grinders may be elevated out of the way, and vice versa. The manner of using the jointing saws 93 and 94 is obvious, but it should be noted that with the construction herein shown and described 15 a beveled or sloping face may be cut by adjusting the swivel head 98 at the requisite angle so that the saw 93 will be inclined at the desired angle to the table 13. The desired angular adjustment may be effected by 20 reason of the fact that the bolts 105 are free to slide in the annular T-groove in the carriage 104.

The usual hand levers for actuating the different clutches shown and described are 25 omitted for the sake of clearness of the drawings.

Provision is made for supplying water to the surface of the work beneath the grinders 14. A flexible supply pipe 141 is connected 30 to distribution pipe 142, from which spouts 143 lead down through the sleeves 35 to the top ends of the grinder shafts 15, which are hollow and form pipes, so that the water is delivered beneath the grinders 14.

35 It is obvious that various modifications may be made in the construction shown and above particularly described within the principle and scope of my invention.

I claim:

40 1. A stone working machine comprising a grinder movable to and from the work, a lever connected with the grinder and having arms extending at opposite sides of a vertical plane in which lies the axis of the lever's fulcrum, and a weight applicable to either arm of the lever and adjustable thereon to vary the pressure of the grinder on the work.

2. A stone working machine comprising a 45 grinder movable to and from the work, a lever connected with the grinder to move the grinder to and from the work, and a cam acting on the lever to regulate the depth of cut of the grinder.

3. A stone working machine comprising a 50 grinder movable to and from the work, a lever connected with the grinder to move the grinder to and from the work, a rock shaft connected with the lever to actuate the lever, and adjustable means for limiting the movement of the rock shaft to regulate the depth of cut of the grinder.

4. A stone working machine comprising a 55 grinder movable to and from the work, a lever connected with the grinder to move the grinder to and from the work, a rock shaft

connected with the lever to actuate the lever, and a handle carried by the rock shaft to move the grinder to and from the work.

5. A stone working machine comprising a 60 grinder movable to and from the work, a lever connected with the grinder to move the grinder to and from the work, a rock shaft connected with the lever to actuate the lever, an arm carried by the rock shaft, and an adjustable stop in the path of the arm to regulate the depth of cut of the grinder.

6. A stone working machine comprising a 65 grinder mounted to rotate in substantially horizontal planes and movable vertically relatively to the work, means for actuating the grinder including a substantially vertical shaft on which the grinder is mounted, a lever connected with the shaft for raising and lowering the grinder, a weight adjustable on the lever to vary the pressure of the grinder on the work, a rock shaft connected with the lever to actuate the lever, an arm carried by the rock shaft, and an adjustable stop in the path of the arm to regulate the 70 depth of cut of the grinder.

7. A stone working machine comprising a 75 grinder mounted to rotate in substantially horizontal planes and movable vertically relatively to the work, means for actuating the grinder including a substantially vertical shaft on which the grinder is mounted, a lever connected with the shaft, a weight adjustable on the lever to vary the pressure of the grinder on the work, a rock shaft, a cam carried by the rock shaft and adapted to actuate the lever, an arm carried by the 80 rock shaft, an adjustable stop in the path of the arm to regulate the depth of cut of the grinder, and a handle carried by the 85 rock shaft to raise and lower the grinder 90 relatively to the work.

8. A stone working machine comprising a 95 grinder movable vertically relatively to the work, means for actuating the grinder, mechanism connected with the grinder for raising and lowering the grinder, a supporting frame for the grinder, a work-supporting table, means for feeding the frame and grinder horizontally relatively to the table, and means actuated by the feeding means and coactive with the raising and lowering mechanism to lift the grinder automatically 100 from one piece of work or from one part of the work to another piece or part of the work.

9. A stone working machine comprising a 105 grinder movable vertically relatively to the work, means for actuating the grinder, a lever connected with the grinder for raising and lowering the grinder, a rock shaft connected with the lever to actuate the lever, an arm carried by the rock shaft, a supporting frame for the grinder, a work-supporting table, means for feeding the frame and grinder horizontally relatively to the table, 110

a push rod coactive with the arm to raise the grinder clear of the work, and a lifting cam stationary relatively to the table and adapted to engage the push rod to lift the grinder from one location on the work to another as the frame is fed relatively to the table.

10. A stone working machine comprising a grinder movable vertically relatively to the work, means for actuating the grinder, a lever connected with the grinder for raising and lowering the grinder, a rock shaft connected with the lever to actuate the lever, an arm carried by the rock shaft, a supporting frame for the grinder, a work-supporting table, means for feeding the frame and grinder horizontally relatively to the table, a push rod coactive with the arm to raise the grinder clear of the work, and a lifting cam stationary relatively to the table and adapted to engage the push rod to lift the grinder from one location on the work to another as the frame is fed relatively to the table, the lifting cam being adjustable 25 to different locations relatively to the table to compel the grinder to be lifted at any desired location relatively to the work.

11. A stone working machine comprising a grinder mounted to rotate in substantially horizontal planes and movable vertically relatively to the work, means for actuating the grinder, mechanism connected with the grinder for raising and lowering the grinder, a supporting frame for the grinder, a work-supporting table, means for feeding the frame and grinder horizontally relatively to the table, and a cam block stationary relatively to the table and coactive with the raising and lowering mechanism to lift 30 the grinder from one location on the work to another as the frame is fed relatively to the table, such cam block being adjustable to different locations relatively to the table to compel the lifting of the grinder to take

place at any desired location relatively to the work.

12. A stone working machine comprising a grinder movable vertically relatively to the work, means for actuating the grinder, mechanism connected with the grinder for raising and lowering the grinder, a supporting frame for the grinder, a work-supporting table, means for feeding the frame and grinder horizontally relatively to the table, a stationary track, and a cam block 55 adjustable along the track and coactive with the raising and lowering mechanism to lift the grinder from one location on the work to another as the frame is fed relatively to the table.

13. A stone working machine comprising a support, a frame mounted to have a feed movement and a return movement relatively to the support, a nut rotatably carried by the support, a screw also rotatably 65 carried by the support and engaging the nut, means for rotating the nut to impart one of said movements to the frame, and means for rotating the screw to impart the other of said movements to the frame.

14. A stone working machine comprising a support, a frame mounted to have a feed movement and a return movement relatively to the support, a nut rotatably carried by the support, a screw also rotatably carried 75 by the support and engaging the nut, means for rotating the nut to impart one of said movements to the frame, and means for rotating the screw to impart the other of said movements to the frame, the means for imparting the feed movement including a worm gear.

In testimony whereof I have affixed my signature in presence of two witnesses.

WILLARD F. MEYERS.

Witnesses:

Wm. ASHLEY KELLY,
BERNARD COWEN.
